UNITED STATES PATENT OFFICE

BURDETTE R. COIBION, OF MAYWOOD, ILLINOIS

DESIGN FOR A BASEBALL GAME BOARD

Application filed March 16, 1931. Serial No. 39,105. Term of patent 7 years.

To all whom it may concern:

Be it known that I, BURDETTE R. COIBION, a citizen of the United States, residing at Maywood, in the county of Cook and State of Illinois, have invented a new, original, and ornamental Design for Baseball Game Board, of which the following is a specification, reference being had to the accompanying drawing, forming a part thereof, in which the figure is a perspective view showing my new design.

I claim:

The ornamental design for a baseball game board as shown.

BURDETTE R. COIBION.
